(No Model.)

J. F. McFADDEN.

ADJUSTABLE CHAIR.

No. 364,273.

Patented June 7, 1887.

UNITED STATES PATENT OFFICE.

JAMES F. MCFADDEN, OF EVANSVILLE, WISCONSIN.

ADJUSTABLE CHAIR.

SPECIFICATION forming part of Letters Patent No. 364,273, dated June 7, 1887.

Application filed May 22, 1886. Serial No. 202,960. (No model.)

To all whom it may concern:

Be it known that I, JAMES F. MCFADDEN, a citizen of the United States, residing at Evansville, Rock county, Wisconsin, have invented 55 certain new and useful Improvements in Adjustable Chairs, of which the following is a specification.

In the drawings, Figure 1 is a perspective of my improved adjustable chair, with the foot-rest elevated and extended and the back inclined. Fig. 2 is a front view of a section taken through the line *u u* of Fig. 1. Fig. 3 is a sectional side view looking from the inside, taken through the line *x x* of Fig. 2. Fig. 4 is a front 15 view of a section taken through line *v v* of Fig. 1. Fig. 5 is a side view of the same portion of the chair. Fig. 6 is a side elevation of the foot-rest, looking from the inside; and Fig. 7 is a front view of the same taken in line *y y* of Fig. 6.

20 A is the main frame-work of the chair; B, the back; C, the foot-rest; D, an extension to the foot-rest; E, the arms; F, a lever extending up by the side of the chair; G, bars extending from the front to the rear legs of the chair at 25 each side and provided with ratchet-teeth; H, an arm-support pivoted to the front ends of the arms and extending down to about the bar G; I, a bar pivoted to the rear end of the arm-support H and extending back to the lever F; 30 J, a dog or pawl adapted to engage the ratchet-teeth in the bar G; K, ratcheted bars supporting the foot-rest; L, a rod extending across the chair from one bar I to the other, and on which the ratchets J are mounted; M, a spring for 35 holding the ratchets in engagement; N, brackets or supports with which the ratcheted bars K engage, and O hooks or loops on the bars I to embrace the bars G.

In making my improved adjustable chair I 40 take a chair with the ordinary main framework, and preferably mounted on rockers. It is immaterial, however, whether my improvement be embodied in a rocking or stationary chair with or without casters. I pivot the 45 back to the upper frame-work at the rear, so that it may be adjusted at different degrees of inclination and be used as a support to the back, in the ordinary use of a chair, or as a support for the body when in a reclining position. I pivot 50 arm-rests to the back frame at a proper height and extend them forward the usual distance.

Pivoted to these arm-rests at a short distance from their front ends are arm-supports H, which extend downward, and are pivoted again to the upper side frames of the chair and extend down below them, and preferably just behind the front legs of the chair, as shown in Fig. 1. I bolt or otherwise securely fasten two ratcheted bars, G, to the front and rear legs of the chair, one at each side. These bars G are provided with ratchet-teeth, as shown in Fig. 1. Pivotally connected to the downwardly-extending ends of the arm supports are supplemental or additional bars I, which pass back immediately above the toothed bars G to a point, say, half-way between the front and rear legs of the chair when in a reclining position, as shown in Fig. 1. The rear ends of these bars I terminate in downward hooks, bends, or loops, which pass around or partially around and embrace the 65 bars G, so as to be held in their proper relative positions and to be moved back and forth along the bars G. Immediately on the inside of these bars I, and at their rear ends and pivoted thereto, are arranged pawls or dogs 70 adapted to engage with the ratchet-teeth of the bars G. A rod, L, extends across from one side of the chair to the other, passing through these pawls or dogs, and to which they are rigidly connected, and through the ends of 75 the bars I. The rod L is permitted to freely turn in the holes in the ends of the rods I. While in turning it raises or lifts the dogs J out of engagement with the teeth in bars G. To operate this rod and to throw the dogs out 80 of engagement at pleasure, so as to adjust the position of the chair, a lever, F, terminating in a suitable handle, extends up to within easy reach of the occupant of the chair, so that by moving it back he can throw the pawls out of 85 engagement and adjust the position of the chair. To hold the dogs in engagement until thus lifted out, a spring, M, (shown in Fig. 3,) is provided. Any spring or weight serving the purpose of holding the dogs in engagement 90 will answer.

To adjust the foot-rest, which is pivoted to the front of the chair-frame, I have two toothed bars or rods, K, pivoted to the same and extending back under the seat of the chair. To 100 the front legs of the chair I preferably, by the same bolts which attach the front ends of the

bars G to the front legs of the chair, secure brackets N. (Shown more particularly in Fig. 4 of the drawings.) These brackets extend upward, and are preferably provided with a 5 cross-rod against which the teeth of the bars K engage. When it is desired to raise the foot-rest to any position, it may be lifted up freely, the teeth of the bars K sliding over the rods in the brackets N, while these teeth engage 10 with such rods when the foot-rest is pressed down and prevent it from falling back into its first position. To lower the foot-rest, the bars K should be lifted enough to permit their teeth to pass back out of engagement 15 with the brackets N. To still further afford a support for the feet, an extension, D, is provided in the foot-rest, which may be pulled out, as shown in Fig. 1, or slid back into position when the foot-rest is lowered. This extension 20 may be given such degree of friction or tightness that it will remain in place, except when voluntarily pulled out for use. This is preferably effected by means of a spring (not shown) which holds the extension in the position to which it has been drawn out, or from coming out voluntarily after being slid back 25 into place.

I have represented my improved chair in plainskeleton form in the drawings. It may be 30 made, however, in upholstery and with any degree of finish and elegance desired. It may be made plain where a cheap and economical chair is preferred, or it may be made with such richness of material and finishings as will suit the

taste of more wealthy and fastidious customers, and, so far as my invention is concerned, of any kind of wood or metal desired. In either case, however, I secure the adjustment of the parts to the various angles and degrees of inclination desired by means substantially 35 as I have above described in detail.

I am aware of the construction shown in the patent to Siebold, of September 10, 1872, and of the construction shown in the patent to Horton, of September 26, 1876, and I do not claim 40 such construction; but in neither of these patents are there shown or described toothed bars connecting the front and rear legs of the chair, nor the simple means, in connection with such bars, for adjusting the angles and positions of 45 the chair.

What I regard as new, and desire to secure by Letters Patent, is—

In an adjustable chair, the combination of main frame, pivoted back pieces, pivoted arms, 50 pivoted arm-supports, ratchet-toothed bars connecting the front and rear legs, supplementary or additional bars pivoted at their front ends to the extended ends of the arm-supports, pawls pivotally connected with the 55 rear ends of the supplementary bars, and means for throwing such pawls out of engagement, substantially as described.

JAMES F. McFADDEN.
